UNITED STATES PATENT OFFICE.

JOSEPH E. BARRANGER, OF PHILADELPHIA, PENNSYLVANIA.

JAR-CLOSURE.

No. 928,098.

Specification of Letters Patent.

Patented July 13, 1909.

Application filed April 1, 1909. Serial No. 487,283.

To all whom it may concern:

Be it known that I, JOSEPH E. BARRANGER, a citizen of the United States, residing in Philadelphia, Pennsylvania, have invented 5 certain Improvements in Jar-Closures, of which the following is a specification.

My invention relates to that particular class of closures for bottles, jars, tumblers or like receptacles, (hereinafter, for convenience, termed a "jar") which are known as "vacuum" closures and in which the cap or cover is held in place upon the jar by the pressure of air thereupon, a vacuum or partial vacuum having been established in the 15 jar.

The object of my invention is to so construct a closure of this class that when the cap or cover is subjected to the pressure of the air and is forced downwardly thereby it 20 will exert a properly applied compressing force upon the sealing gasket used in connection therewith and will have no tendency to distort said gasket or displace it from its seat below the mouth of the jar, another object of 25 the invention being to so shape the sealing gasket that it can be cut from a tube of proper diameter without waste.

In the accompanying drawing—Figure 1 is a vertical sectional view, on an enlarged 30 scale, of the upper portion of a jar constructed and provided with a sealing gasket and cover in accordance with my invention; Fig. 2 is a similar view, illustrating the relation of the parts to one another after the vacuum 35 has been established, the cover subjected to the air pressure and the sealing of the jar effected, and Fig. 3 is a view similar to Fig. 2, but illustrating a modified construction of the seat formed upon the jar for the reception 40 of the sealing gasket.

In the drawing, 1 represents part of the body of the jar which has, on the outside of the same immediately below the mouth, a vertical wall 2 terminating at its base in a 45 horizontal shoulder 3, a rib 4, preferably rounded on its outer face, being located at the angle which would otherwise be formed between the vertical wall 2 and horizontal shoulder 3.

50 In connection with the jar thus constructed I employ a sealing gasket 5 of wedge-shaped cross section, said gasket having a vertical face for contact with the wall 2 of the jar and a horizontal face for resting upon the 55 horizontal shoulder 3, and having inner and outer beveled faces, the inner beveled face,

when the gasket is first applied to the jar, bearing lightly upon the rib 4 at the junction of the vertical wall 2 and horizontal seat 3, as shown in Fig. 1.

60 The cap 6 has a depending flange with reversely curved portion 7, and when said cap is first applied to the jar this depending flange rests upon the outer face of the sealing gasket 5 but permits ready escape of the 65 air from the interior of the jar when the vacuum is established in the chamber containing said jar.

When downward pressure is applied to the cap the shoulder 3 prevents downward movement of the gasket, and the vertical wall 2 of the jar prevents inward movement of the same, consequently compression is exerted upon the gasket 5 substantially in the direction of the arrows *x* in Fig. 1, so as to force 75 the inner face of the gasket over the projecting rib 4, press its inner and bottom faces firmly against the vertical wall and horizontal shoulder of the jar and drive the surplus material upwardly between said vertical wall 80 of the jar and depending portion of the cap and downwardly on the outside of the horizontal shoulder 3 of the jar, the diameter of the lower portion of the cap being so much in excess of the diameter of the shoulder as 85 to permit this action.

Below the shoulder 3 the jar has a projecting rib 9, which projects slightly beyond the depending flange of the cap and prevents loosening of said cap by protecting the lower 90 edge of the flange from upward pressure.

95 In some cases I may substitute a beveled face 4^a for the rib 4 at the junction of the vertical wall and horizontal shoulder of the jar, but the rib is preferred, owing to the positive indentation of the inner face of the sealing gasket caused thereby, and the more secure joint caused by reason of such indentation.

The wedge-shaped gaskets 5 can be readily 100 cut from a tube without waste, by forming reversely inclined diagonal cuts in said tube.

I claim:

1. The combination of a jar having a vertical face, a horizontal shoulder and a seat 105 at the junction of the two with a wedge-shaped packing gasket presenting faces for contact with the vertical wall, horizontal shoulder and intervening seat, and a cap having a portion for pressing upon the bevelled outer face of the gasket.

2. The combination of a jar having a ver-

tical wall, a horizontal shoulder and a ribbed seat at the junction of the two, with a wedge-shaped sealing gasket having faces bearing against the vertical wall, horizontal shoulder and ribbed seat of the jar, and a cap having a portion for bearing upon the beveled outer face of the gasket.

In testimony whereof, I have signed my name to this specification, in the presence of two subscribing witnesses.

JOSEPH E. BARRANGER.
